UNITED STATES PATENT OFFICE.

MAX VIEK, OF NEW YORK, N. Y.

CHAIR.

Application filed June 30, 1925. Serial No. 40,473.

To all whom it may concern:

Be it known that I, MAX VIEK, a citizen of Germany, residing at New York, in the county of New York and State of New York, have invented certain new and useful Improvements in Chairs, of which the following is a specification.

This invention relates to chairs and has for its object to provide a chair for a bass violin player, which will permit the latter to occupy a sitting position in the orchestra, while playing the instrument.

Another object is to make the chair collapsible, so that it may be conveniently carried from place to place.

Heretofore, as is well-known, of all the players of an orchestra the bass violin player has been the only player, who, because of the size of his instrument, has had to occupy a standing position, while playing his instrument, which is not only very tiresome, but generally causes flat feet.

Attempts have already been made to construct chairs suitable for bass violin players but with no success.

The chair, in order to answer the purpose, must fulfill several requirements.

In the first place, the seat of the chair must be at a higher elevation than that of an ordinary chair, and must be so shaped as to permit the legs of the player to occupy certain positions while the instrument is being played. Then the chair must afford proper supports for the feet of the player, which will permit the player, while occupying a sitting position, to support the instrument with one leg, while his other leg will be stretched, so as not to interfere with the movement of the arm using the bow.

Another requirement is that the supports for the feet must be capable of being easily adjusted into different positions by the feet of the player occupying the seat, to suit the convenience of the player.

Still another requirement is that the chair be easily and quickly collapsible into a flat body, so that it may be accommodated in an appropriate sheath and conveniently carried through the streets, subways, etc., just like the instrument itself.

The chair, according to the present invention, answers all these requirements and satisfies a long felt desideratum in the equipment of an orchestra band.

While in the following I will describe one embodiment of my invention, I wish it

to be expressly understood that various changes may be made in the construction by those skilled in the art without departing from the principle of this invention.

In the accompanying drawing, which forms part of this specification and in which similar reference characters denote corresponding parts, Fig. 1 is a perspective view of my new chair shown unfolded into the position of use; Fig. 2 is a front elevation of the collapsed chair; Fig. 3 is a side elevation thereof; Fig. 4 is a longitudinal section on line 4-4 of Fig. 2; Fig. 5 is a perspective view of the joint between the collapsible rear legs of the chair and the back of the latter; Fig. 6 is a similar view of a joint between the seat and the rear legs thereof and Fig. 7 is a front elevation of one of the foot supporting stools or wings and its joint with the main frame of the chair.

The chair comprises a main frame 10 carrying the seat, back and supports for the feet and a collapsible frame 11 serving, when unfolded, as the rear legs. The main frame is substantially of rectangular shape and is composed of a pair of side bars 10' joined together by a plurality of cross bars 10². The bottom edges 10³ of said side bars are cut on a bias, so as to rest flatly on the floor, when the chair is in use. The seat 12 is substantially of trapezoidal shape, the parallel side edges 12' thereof being pivotally joined to the side bars 10' of the main frame, as for instance by a cross rod 13 fixed in the seat and the ends of which are journaled in apertures of the side bars, as at 13'. The rear edge 12² of the seat is substantially perpendicular to the side bars 10', while the front edge 12³ thereof is cut on a bias, so that when the chair is in use, the player's right leg will be allowed to be held in a downwardly stretched out position, while his left leg with its thigh portion will be supported on the seat, as indicated by dotted lines in Fig. 1, so that the bass violin may be allowed as usual to lean against the left leg and thereby be supported in proper position, while the right leg will be out of interference with the movement of the arm carrying the bow. The back 14, which may be of any shape and construction, such as shown, near its upper edge is pivotally supported in the side bars 10' in a similar manner to the seat, that is, by means of a cross rod 15 whose ends are

2

journaled in apertures of the side bars 10'. The width of the side bars 10' of the main frame is made larger than the total thickness of the back and seat, so that, when the 5 chair is collapsed, the back and seat will overlap one another extending through planes parallel to the plane of the main frame and entirely confined within the space bounded by the side bars of the main frame.

10 The rear or auxiliary frame 11 is composed of a pair of parallel side bars 11' and cross rods or bars 11², the side bars 11' being narrower than those of the main frame 10 and the cross rods or bars 11² being slightly 15 shorter than the side bars of said main frame, so that in collapsed position the auxiliary frame like the seat and back will be confined within the space bounded by the side bars of the main frame. The upper 20 ends of the side bars 11' of the auxiliary frame 11 are pivotally joined to the corresponding side bars 10' of the main frame, as at 11³, and to this end, the lower portion 25 of the back 14 is cut away at its sides, as at 14', to accommodate the pivoted ends of 30 said side bars 11' between themselves and the side bars 10' of the main frame. The lower part of the back has pivotally attached to its cut-away sides, as at 16', U-shaped 35 members 16, which are adapted to slidably engage the upper ends of the side bars 11' and to thus serve as additional supports for the lower portion of the back, yet permitting 40 the rear frame 11 to swing into the collapsed and unfolded positions. The rear part of the seat is cut away at its sides, as at 12^a, about the thickness of the side bars 11', and has fixed to said cut-away sides U-shaped members 17 having a perpendicularly 45 extending projection 17' formed with a pin 18. These pins 18 are adapted to slidably engage longitudinal grooves 11^a provided on the inner faces of said bars 11' and when abutting against the upper ends of said 50 grooves to serve as means for retaining the seat in its horizontal position. Simultaneously this slidable connection between the seat 12 and the auxiliary frame 11 serves as a means whereby, while tilting the seat into collapsed or extended position, the auxiliary frame will be automatically moved into the corresponding position.

For the support of the feet of the player, while the chair is in use, I employ collapsible 55 foot stools 20, 21 each composed of two sections 20^a, 20^b and 21^a, 21^b respectively, hinged or pivotally connected together as at 22. The sections 20^b and 21^b serve as 60 legs for said stools and are of different lengths, the lower stool serving as a support for the extended right leg and the higher stool for the bent leg. The sections 20^a and 21^a are connected to the corresponding side bars 10' of the main frame by suitable universal joints, which permit the stools to be

collapsed or folded to extend longitudinally of said bars, when the chair is not in use, and when unfolded, to swivel in horizontal direction, so that the player, while occupying the chair, may, with his feet, easily adjust 70 the stools to positions most convenient for him, while playing the instrument. In the present embodiment of my invention, I employ as a joint a hinge 23 whose one wing 23' is fixed to the corresponding side bar, as at 23^a and whose other wing is of U-shaped cross-section engaging the foot supporting section of the corresponding stool by means of a vertical pin 22^b. When not 75 in use, the sections of the stools are folded upon themselves and upon the side bars of the frame extending longitudinally of the latter and are hooked or otherwise secured in this folded position, as at 24. In this collapsed position, the entire chair forms a 80 perfectly flat body substantially of rectangular shape and can be easily accommodated in a suitable sheath and transported from place to place.

85 The sections 20^b, 21^b, which serve as the legs of the stools, may be made of adjustable length and likewise the swivel joints may be adjustably fixed to the side bars of the main frame, so as to permit adjustment of the elevation of the stools according to the size 90 of the player using the chair. Provision also may be made for raising and lowering the seat for a similar purpose.

95 What I claim is:—

1. A chair for bass violin players, comprising a frame, a highly elevated seat thereon whose front edge is horizontally slanting and foot stools of different elevations attached to said frame. 100

2. A chair for bass violin players, comprising a collapsible frame, a collapsible highly elevated seat thereon whose front edge is horizontally slanting and collapsible horizontally movable foot stools of different elevations attached to said frame, said chair, 105 when collapsed, forming a flat body. 110

3. A chair for bass violin players, comprising a main frame, an auxiliary frame pivoted thereto to be collapsible into said main frame and serving in unfolded position as rear legs for said chair, a highly elevated vertically swinging seat whose front edge is horizontally slanting and which engages said auxiliary frame, so that, when unfolded, it will be retained thereby 115 in the unfolded position and when tilted into collapsed or unfolded position, it will automatically move said auxiliary frame into the corresponding position and collapsible foot stools on said main frame. 120

4. A chair for bass violin players, comprising a main frame, an auxiliary frame pivotally connected to said main frame, a back pivotally connected to the former and 125 slidably engaging said auxiliary frame, a 130

highly elevated seat pivoted to said main frame and having a horizontally slanting front edge, laterally projecting members on said seat slidably engaging said auxiliary frame and serving to retain said seat in unfolded position and for automatically moving said auxiliary frame simultaneously with the movement of said seat into collapsed or unfolded position and lateral foot 5 stools of different elevations joined to said main frame so as to be collapsible and adjustable horizontally to different positions.

5. A chair for bass violin players having a highly elevated seat whose front edge is horizontally slanting and lateral horizontally swivelling foot stools of different elevations.

6. A chair for bass violin players having a highly elevated collapsible seat whose front edge is horizontally slanting and horizontally movable collapsible lateral foot 10 stools of different elevations.

In testimony whereof I affix my signature.
MAX VIEK.
